(57) **CLAIM**

We claim the ornamental design for a writing instrument, as shown and described.

DESCRIPTION

FIG. 1 is a front, upper perspective view showing our new design for a writing instrument in a retracted state.

FIG. 2 is a rear, upper perspective view showing the design of FIG. 1.

FIG. 3 is a first side view showing the design of FIG. 1.

FIG. 4 is a second side view showing the design of FIG. 1.

FIG. 5 is a third side view showing the design of FIG. 1.

FIG. 6 is a fourth side view showing the design of FIG. 1.

FIG. 7 is a top view showing the design of FIG. 1.

FIG. 8 is a bottom view showing the design of FIG. 1.

FIG. 9 is a side view showing the writing instrument of FIG.

1 in an extended, unretracted state; and,

FIG. 10 is a bottom view showing the design of FIG. 9.

1 Claim, 7 Drawing Sheets
